UNITED STATES PATENT OFFICE.

WILLIAM E. HERMAN, OF ALLEGHENY, PENNSYLVANIA, ASSIGNOR OF ONE-HALF TO ROLAND
MacGREGOR, OF KNOXVILLE BOROUGH, PENNSYLVANIA.

MACHINE FOR CUTTING OVALS.

No. 877,422.

Specification of Letters Patent.

Patented Jan. 21, 1908.

Application filed July 5, 1907. Serial No. 382,300.

To all whom it may concern:

Be it known that I, WILLIAM E. HERMAN, a citizen of the United States of America, residing at Allegheny, in the county of Allegheny and State of Pennsylvania, have invented certain new and useful Improvements in Machines for Cutting Ovals, of which the following is a specification, reference being had therein to the accompanying drawing.

This invention relates to a machine for cutting ovals, the machine being designed for cutting various kinds of material, principally glass.

My invention aims to provide a novel machine wherein positive and reliable means are employed for adjusting the major and minor axes of an ellipse or oval. In this connection, the machine is primarily intended as a mirror

or cutting machine, whereby an oval or elliptical mirror can be accurately, economically and expeditiously cut. To this end, I have devised a machine somewhat upon the principle of a vertical lathe, wherein an adjustable cutter head is used together with an adjustable work support, which is set to automatically move a piece of work beneath the cutter head and describe an oval or ellipse having true and predetermined axes.

The detailed construction entering into my invention will be presently described, and reference will now be had to the accompanying drawings, in which,

Figure 1 is an elevation of a machine constructed in accordance with my invention. Fig. 2 is a plan of the same. Fig. 3 is a plan of a portion of a machine illustrating the movable platform thereof. Fig. 4 is a longitudinal sectional view of the same, and Fig. 5 is a cross sectional view.

I construct the machine of a base plate or foundation 1 having at its one end a post or standard 2 provided with a vertically disposed dove-tail tongue 3 and with a vertically disposed rack 4. Slidably mounted upon the tongue 3 is an outwardly extending arm 5 having a longitudinally disposed slot or groove 6 formed therein. The arm 5 is adjusted with relation to the post or standard 2 by a pinion 7 carried thereby, meshing with the rack 4, said pinion being rotated by a crank 8.

Slidably mounted in the groove or slot 6 of the arm 5 is a housing 9, said housing being adjusted by a screw 10 revolvably

mounted in hangers 11, carried by the arm 5. The outer end of the arm 5 is provided with a dial 12, in front of which rotates a crank 14 carried by the screw 10 for adjusting the housing 9 through the medium of the screw 10. The crank 14 carries an indicator or pin 15 for determining the position of the housing 9. Journaled in the housing 9 is a vertically disposed shaft 16 carrying upon its lower end a cutter head 17, while its upper end is provided with a beveled gear wheel 18 meshing with a beveled gear wheel 19 slidably keyed upon a shaft 20 journaled in bearings 21, carried by the arm 5. The beveled gear wheel 19, besides sliding upon the shaft 20, is adapted to rotate therewith, and is normally held in engagement with the beveled gear wheel 18 by a bracket 22 carried by the upper end of the housing 9.

The inner end of the shaft 20 is provided with a beveled gear wheel 23 meshing with a similar wheel 24, this wheel 24 being revolvably connected to a bracket 25 carried by the arm 5. Passing through the bracket 25 and the beveled gear wheel 24 is a vertically disposed shaft 26, said shaft being keyed to the beveled gear wheel 24, whereby said gear wheel will rotate with said shaft and at the same time permit of the arm 5 and its appurtenant parts remaining operatively connected to the shaft 26. The shaft 26 is journaled in bearings 27 carried by the post or standard 1 at one side of the arm 5, whereby said shaft will not interfere with the vertical adjustment of the arm 5. The lower end of the shaft 26 carries a beveled gear wheel 28 meshing with a similar wheel 29 mounted upon a driven shaft 30, said shaft being journaled in a bearing 31 carried by the base plate or foundation 1 of the machine. The shaft 30 can be driven by a motor (not shown) or from any source of power.

Secured to the standard or post 2, as at 32, is a support 33, said support extending outwardly beneath the adjustable arm 5, and being apertured to receive the shaft 26. The support 33 is slotted, as at 34, and provided with a longitudinally disposed groove 35 for a block 36, said block having a depending stem 37 provided with a threaded opening 38. Extending through the threaded opening 38 is a screw 39 revolvably mounted in hangers 40, carried by the support 33. The outer end of the screw 39 carries a crank 41 having an indicator or pin 42 for engaging a

dial 43, similar to the crank 14 and the dial 12 of the arm 5 the dial 43 being carried by the support 33. The dial 43 determines the position of the block 36 and the parts carried thereby. Centrally of the support 33 and over the groove 35 is mounted a circular plate 44 having a slot 45 for a post 46, carried by the block 36. Surrounding the plate 44 is a revoluble band 47 carrying 10 two parallel guides 48, and resting upon said guides are parallel angle bars 49 carrying a table 50. The bottom of the table 50 is provided with a longitudinally disposed groove 51 to receive a head 52 fixed upon the post 46, 15 as at 53. The table is cut away, as at 54, to clear the upper end of the post 46, and is provided with a central opening 55.

The table 50 is revolved by a belt 56 passing around the revoluble band 47, said belt 20 being driven from a suitable source of power, or, its mechanical equivalent can be used for imparting a rotary movement to the table 50. This table has been illustrated as oval in plan, but the same can be made of any desired 25 shape as long as it clears the post or standard 2 during its rotary movement, irrespective the position it may be adjusted to.

In operation, the adjustment of the housing 9 determines the major axes of the ellipse 30 or oval to be cut by the head 17, while the adjustment of the table 50 determines the minor axes of an oval or ellipse. The piece of work to be operated upon is placed upon the table 50 and can be suitably secured thereto by 35 clamps (not shown) or similar fastening means. When the screw 10 has been adjusted through the medium of the crank 14, to determine the major axes of the oval to be cut from the material upon the table 50, the 40 arm 5 is ready to be lowered to place the cutter head 17 in engagement with the material upon the table. The minor axis of the ellipse is now determined by adjusting the screw 39 through the medium of the crank 41. The 45 left hand ends of the slots 34 and 45 align with the central opening 55 of the table 50, consequently when the block 36 is adjusted to retain the post 46 at the left hand end of the slot 45, the table 50 will concentrically 50 revolve, when a rotary movement is imparted to the band 47 by the belt 56. If the post 46 is moved off-center, and the rotary movement of the band 47 continued, the table will 55 revolve eccentrically, that is to say the table 50 will slide back and forth upon the guides 48, and since the head 52 is revolubly mounted upon the post 46, the head will move back and forth in the groove 51. While the cutter head 17 remains stationary, the 60 table 50 and material thereon is guided, causing the cutter-head to describe an oval upon the material on the table, the major and minor axes of the oval having been previously determined by the adjustment of the 65 cranks 14 and 41.

I attach considerable importance to the novel construction of the support 33 and its adjustable and movable table, as the movements of this table with relation to a stationary cutter head determines the exact size of 70 an oval.

The major axis of an ellipse is limited by the length of the screw 10 and the slot 6, while the minor axis is limited by the length of the slot 34. It is therefore apparent that 75 the size of an oval entirely depends upon the size of the machine, large machines producing large ovals and small machines small ovals.

Having fully described my invention, what 80 I claim and desire to secure by Letters Patent is:

1. In an oval cutting machine, the combination of an adjustable slotted arm an adjustable housing carried by said arm, a shaft journaled in said housing, a cutter head carried thereby, a support located beneath said arm, said support having a groove and slot formed therein, a block adjustably mounted in the groove of said support, a slotted plate mounted upon said support, a revoluble band surrounding said plate, guides secured to said band, a post carried by said block and extending through the slot of said plate, a head carried by said post, a table 95 slidably mounted upon said head and upon said guides, and means for rotating said shaft.

2. In an oval cutting machine, the combination with an adjustable rotary cutter head, of a support located beneath said head, 100 said support having a groove formed therein, a block adjustably mounted in said groove, a slotted plate mounted upon said support, a revoluble band surrounding said plate, guides carried by said band, a post carried by 105 said block and extending through said plate, a head revolubly mounted upon said post, and a table slidably mounted upon said head and said guides, substantially as described.

3. In an oval cutting machine, the combination with a cutter head, of a support beneath said head, a block adjustably mounted in said support, a band revolubly mounted upon said support, guides carried by said band, a revoluble head supported by said block, and a table slidably mounted upon 115 said guides and said head.

4. In an oval cutting machine, the combination with a cutter head, of a support, a revoluble ring concentrically mounted upon 120 said support, a revoluble head adjustably supported from said support, guides carried by said band, and a table slidably mounted upon said head and said guides.

5. A table for cutting machines, embodying a stationary support provided with a slot and having a recess in its upper face, a block movably mounted in said recess and having a stem projecting through said slot, a screw carried by the support and engaging said 130

stem for adjusting said block, a slotted plate mounted on said block and support, a post carried by said block and projecting through the slot in said plate, a head carried by said post, a table mounted on said head and having a groove to receive the latter, and means for rotating said plate and thereby imparting rotary movement to the table.

6. In an oval cutting machine, the combination with a support, of an arm carried by said support and adjustable vertically thereon, a housing carried by the arm and adjustable towards and away from the support, means carried by the arm and engaging the

housing for adjusting the latter on the arm, a cutter head carried by said housing, means for operating said cutter head, a table support connected to the first mentioned support, a table rotatably mounted on said table support, and separate means for rotating said table on its support independently of the cutter head rotating means.

In testimony whereof I affix my signature in the presence of two witnesses.

WILLIAM E. HERMAN.
